US00D567793S

(12) **United States Design Patent** (10) **Patent No.:** **US D567,793 S**
Eguchi (45) **Date of Patent:** **** Apr. 29, 2008**

(54) **HANDSET**

(75) Inventor: **Shunjiro Eguchi**, Helsinki (FI)

(73) Assignee: **Nokia Corporation**, Espoo (FI)

(**) Term: **14 Years**

(21) Appl. No.: **29/277,429**

(22) Filed: **Feb. 26, 2007**

(30) **Foreign Application Priority Data**

Aug. 30, 2006 (FI) M20060163

(51) **LOC (8) Cl.** **14-03**

(52) **U.S. Cl.** **D14/138**

(58) **Field of Classification Search** D14/137, D14/138, 147, 148, 150, 168, 191, 218, 247-248, D14/341-347, 496; D10/65; D13/168; D18/7; 455/90.3, 556.1, 556.2, 575.1, 575.3, 575.4; 379/433.01-433.13; 361/814; 348/14.02

See application file for complete search history.

(74) *Attorney, Agent, or Firm*—Banner & Witcoff, Ltd.

(57) **CLAIM**

The ornamental design for a handset, key button area for a handset, and set of key buttons for a handset, as shown and described.

DESCRIPTION

FIG. 1 is a bottom plan view of a handset showing my new design;

FIG. 2 is a right side view thereof;

FIG. 3 is a front view thereof;

FIG. 4 is a left side view thereof;

FIG. 5 is a top plan view thereof;

FIG. 6 is a rear view thereof;

FIG. 7 is a perspective front view thereof;

FIG. 8 is a perspective rear view thereof;

FIG. 9 is a front view of the handset of FIGS. 1-8 in a first position;

FIG. 10 is a perspective front view thereof;

FIG. 11 is a rear view thereof;

FIG. 12 is a right side view thereof;

FIG. 13 is a left side perspective front view of FIGS. 1-8 in a second position;

FIG. 14 is a right side perspective front view thereof;

FIG. 15 is a perspective rear view of FIGS. 1-8 in a third position; and,

FIG. 16 is a perspective front view thereof.

The broken line showing of a remainder of the handset is for illustrative purposes only and forms no part of the claimed design.

1 Claim, 10 Drawing Sheets
